(57) **CLAIM**

The ornamental design for a network switch, as shown and described.

DESCRIPTION

FIG. 1 is top, front, right, perspective view of a network switch showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The dot-dash broken lines and evenly spaced broken lines immediately adjacent to the shaded areas represent the bounds of the claimed design, while all other broken lines are directed to the environment. The broken lines form no part of the claimed design.
